(57) **CLAIM**

The ornamental design for a storage container, as shown and described.

DESCRIPTION

FIG. 1 is a top perspective view of a storage container of the present invention.

FIG. 2 is a rear perspective view of the storage container of FIG. 1.

FIG. 3 is a front elevational view of the storage container of FIG. 1.

FIG. 4 is a rear elevational view of the storage container of FIG. 1.

FIG. 5 is a right side elevational view of the storage container of FIG. 1; the left side elevational view of the storage container being a mirror image thereof.

FIG. 6 is a top plan view of the storage container of FIG. 1.

FIG. 7 is a bottom plan view of the storage container of FIG. 1.

FIG. 8 is a cross-sectional view of the storage container of FIG. 1, taken along section line A-A as depicted in FIG. 6.

FIG. 9 is a cross-sectional view of the storage container of FIG. 1, taken along section line B-B as depicted in FIG. 6.

FIG. 10 is a cross-sectional view of the storage container of FIG. 1, taken along section line C-C as depicted in FIG. 6.

FIG. 11 is a cross-sectional view of the storage container of FIG. 1, taken along section line D-D as depicted in FIG. 6.

FIG. 12 is a cross-sectional view of the storage container of FIG. 1, taken along section line E-E as depicted in FIG. 6.

FIG. 13 is a cross-sectional view of the storage container of FIG. 1, taken along section line F-F as depicted in FIG. 6.

FIG. 14 is a cross-sectional view of the storage container of FIG. 1, taken along section line G-G as depicted in FIG. 6.

FIG. 15 is a cross-sectional view of the storage container of FIG. 1, taken along section line H-H as depicted in FIG. 6.

FIG. 16 is a cross-sectional view of the storage container of FIG. 1, taken along section line I-I as depicted in FIG. 6; and,

FIG. 17 is a cross-sectional view of the storage container of FIG. 1, taken along section line J-J as depicted in FIG. 6.

The broken lines shown on the storage container in FIGS. 1-17 are for illustrative purposes only and form no part of the claimed design.
